UNITED STATES PATENT OFFICE.

WILLIAM H. ASH, OF BAY SHORE, NEW YORK.

GAS-ENGINE.

No. 877,753.

Specification of Letters Patent.

Patented Jan. 28, 1908.

Application filed April 5, 1906. Serial No. 310,155.

To all whom it may concern:

Be it known that I, WILLIAM H. ASH, a citizen of the United States of America, residing at Bay Shore, in the county of Suffolk, State of New York, have invented certain new and useful Improvements in Gas-Engines, of which the following is a specification.

It is the main object of my invention to provide mechanism whereby an explosion or gas engine of a common type or a non-reversible engine especially constructed with the improvements herein shown, may be readily changed from two to four cycle at the will of the operator.

Other objects of my invention, such as the construction of the peculiar form of carbureter necessary, and the utilization of the residual air and gases after the explosion while the engine is run at four cycle will be obvious from the description as hereinafter set forth.

In the accompanying drawings Figure 1 is a diagrammatic plan view of a preferred form of gas engine with my improvements applied thereto; Fig. 2 is a vertical section of an engine showing the arrangement of the ports and lubricating system; Fig. 3 is a sectional view of a preferred form of carbureter; and Figs. 4, 5, and 6 are views of modifications.

Referring to the drawings, Figs. 1 and 2, 10 represents the cylinder with crank case 14 having bearings for a crank, a shaft 11 with a balance wheel 12. The crank of the shaft 11 is connected to the piston 13 by the rod 13¹. The cylinder is provided with an exhaust port 101 on one side, and an inlet port 102 from the crank chamber on the opposite side. At the end of the explosion stroke the burned gases exhaust direct into the atmosphere and the fresh charge which has been compressed meanwhile in the crank chamber immediately rushes in as soon as 45 the port 102 is opened. A suitable deflector 133 may be placed on the upper side of the piston head to direct the gas to the upper part of the cylinder.

On the shaft 11 two gears 15, 16, are provided adapted at all times to engage and rotate gears 17 and 18 respectively, on separate shafts 19, 20. The gear 17 meshes with the gear 15 in the proportion of two to one, while the gears 18 and 16 are equal. Both 55 gears 17 and 18 are elongated sufficiently to permit lateral movement for the purpose

about to be described, without disengagement of the gears.

On the shafts 19, 20, are grooved collars 21 and 22 respectively, engaged by the forked ends of a shifting rod 23 provided with a suitable handle or other operating means 24. Also on these shafts are circuit closers 25, 26, one (25) adapted to contact with the terminal 27 of the sparking circuit and the other (26) to contact with the terminal 28 according as the engine is to run four or two cycle, as hereinafter described. Either cam 29 or cam 30 at the adjacent ends of the shafts 19 and 20 may be brought into position to engage and operate a roller 31 on the pivoted arm 32 on the casing of the carbureter 33. A cam 34 is also placed on the shaft 19 for engaging suitable lever mechanism 42 for operating an exhaust valve in port 35 on top of the cylinder, when the engine is running four cycle, as will be described later.

From this description it will be readily seen that the engine when in the position shown will operate as a two-cycle engine, the shafts 11 and 20 through the gears 16 and 18 will cause the carbureter valve by means of the cam 30 to be opened at each revolution, and the charge to be ignited at each revolution by the closing of the sparking circuit. Although the gear 17 revolves during the same period, the circuit closer 25 and cams 29 and 34 are out of action, and no effect is produced thereby. By shifting the rod 23 to the right, the shafts 19 and 20 will move with all the attached parts correspondingly. The circuit closer 25 will then contact with the terminal 27 and the cam 29 engage the roller 31, but as this shaft turns only half as fast as the shaft 20 the carbureter valve will be operated once at every other revolution, or at four cycle, and the circuit closer 25 will also complete the circuit to the spark plug at every other revolution. After shifting the shafts the cam 30 and circuit closer 26 will be out of engagement with the roller 31 and terminal 28.

When the mechanism is adjusted to run 4-cycle, the cam 34 will act on the lever mechanism 42 (Fig. 1) to open the exhaust valve 40 (Fig. 2) at the proper time.

My preferred form of carbureter valve (Fig. 3), consists of a casing 33 having a pivoted rod 32 with roller 31 adapted to be engaged at the end by a cam 30, or 29, as previously described and shown in Fig. 1.

Within this casing is a valve 60 with a valve seat and a stem 61 passing through a stuffing box 62 in the top of the casing. This stem 61 is provided with a vertical slot 61¹ to permit a free downward movement of the rod 32. A spring 63 abutting against a collar 64 on the stem normally holds the valve closed and the rod 32 in the upper part of the slot 61¹. This spring may be either on the upper 10 or lower side of the top of the casing (Figs. 3 and 4). A needle valve 65 of any suitable style supplies the explosive liquid, which is vaporized on the inrush of air on lifting the valve, due to the vacuum in the crank chamber. The mixture then passes through the 15 passage 66 to the crank chamber of the engine. From this construction it will be seen that it is impossible to reverse the engine, for should the cam for any reason turn in a direction opposite to the arrow, the rod 32 will be raised instead of depressed and its opposite end will move freely in the slot 61¹ compressing the spring and closing the valve tighter, thereby positively preventing a 20 fresh charge entering the crank chamber.

The modification shown in Fig. 5 shows a carbureter valve of similar construction, but the cam engages the end of the rod that raises the valve from its seat in such a manner that the engine may be reversed if desired. By similarly placing the cam (Fig. 3) 30 the same object may be accomplished if desired.

Fig. 6 shows a gravity valve which is 35 opened by the vacuum caused in the crank chamber when the engine is running either cycle. The stem to this valve is of course first raised by mechanism similar to the construction shown in connection with Fig. 3.

40 With any one of these carbureter valves the cam 30, or cam 29, is so placed on the shaft that the valve is not opened until the piston is at the top of the stroke and has forced all the air out of the cylinder. When 45 the piston is up a vacuum is created in the crank chamber, and the proper amount of air rushes in as soon as the valve 60 is opened.

I claim as my invention:

50 1. A gas engine comprising a cylinder and piston, a driving shaft, an exhaust port opened by the piston at the end of the explosion stroke in combination with a carbureter for supplying gas to the cylinder, a 55 sparking circuit to explode the gas in the cylinder, and means for operating said carbureter and sparking circuit either at every or every other revolution of the crank shaft for the piston.

60 2. A gas engine comprising a cylinder and piston, an exhaust port opened by the piston at the end of the explosion stroke, in combination with a carbureter and sparking circuit, two shafts driven from the engine, one 65 at half the speed of the other, and means for

operating the carbureter and sparking circuit from either of said shafts, whereby the engine may be run at two cycle or four cycle.

3. A gas engine comprising a cylinder and piston, an exhaust port opened by the piston at the end of the explosion stroke, in combination with a carbureter and sparking circuit and two shafts driven from the engine, each shaft having a cam to operate the carbureter and a circuit closer to operate the 75 sparking circuit, whereby the engine may be run at two cycle or four cycle.

4. A gas engine comprising a cylinder and piston, an exhaust port opened by the piston at the end of the explosion stroke, a driving 80 shaft, gears on said shaft, a carbureter for supplying gas to the engine and a sparking circuit to explode the same, in combination with means operatively connected with said gears for operating said carbureter and 85 sparking circuit either at every or every other revolution of the crank shaft for the piston.

5. A gas engine comprising a cylinder and piston, an exhaust opened by the piston at the end of the explosion stroke, a driving 90 shaft, gears on said shaft, and a carbureter for supplying gas to the engine in combination with means comprising two independent shafts, gears thereon meshing with said first gears, and cams, means adapted to be engaged by the cams for operating the carbureter valve, and means for shifting the 95 shafts for running the engine two cycle or four cycle.

6. A gas engine comprising a cylinder and 100 piston, an exhaust opened by the piston at the end of the explosion stroke, a driving shaft and two gears on said shaft, in combination with means comprising two other shafts, a gear on each shaft meshing with a 105 gear on the driving shaft and means for operatively connecting these gears whereby the engine is run two cycle or four cycle, one pair of gears being in the proportion of two to one and the other pair being equal. 110

7. A gas engine comprising a cylinder and piston, an exhaust opened by the piston at the end of the explosion stroke, in combination with an outlet valve at the outer end of the cylinder and means for admitting an explosive charge to said cylinder and means for exploding the same on either every or every other revolution of the crank shaft of the piston. 115

8. A gas engine comprising a cylinder and 120 piston, a driving shaft and a carbureter, in combination with means for keeping the carbureter valve closed on a reversal of the engine.

9. A gas engine comprising a cylinder and 125 piston, a driving shaft and a carbureter, in combination with a carbureter valve, a slotted spindle operating in connection therewith, a rod working in the slot of said spindle and means for operating said rod to actu- 130

ate the spindle only on the forward drive of the engine.

10. A gas engine comprising a cylinder and piston, a driving shaft and a carbureter, in combination with a carbureter valve, a slotted spindle operating in connection therewith, a rod working in the slot of said spindle and means for operating said rod on the reversal of the engine to insure the continual closure of the valve.

11. A gas engine comprising a cylinder and piston, a driving shaft and a carbureter, in combination with a carbureter valve, a slotted spindle operating in connection there-

with, a rod working in the slot of said spindle 15 and a cam operating from the driving mechanism of the engine to actuate said rod so as to open the carbureter valve only on the forward drive of the engine, substantially as described.

20 In testimony whereof I have signed my name to this specification, in the presence of two subscribing witnesses.
